SEWING MACHINE

Oscar Quist, Chicago, Ill., assignor to Union Special Machine Company, Chicago, Ill., a corporation of Illinois

Original application December 30, 1939, Serial No. 311,722, now Patent No. 2,345,992, dated April 4, 1944. Divided and this application February 26, 1943, Serial No. 477,189

3 Claims. (Cl. 112—237)

1

This invention relates to sewing machines, and more particularly to mechanism provided in such machines for lifting a presser foot which is arranged to retain work against a base or other work support.

The present case is a division of application Ser. No. 311,722, filed on December 30, 1939, now Patent No. 2,345,992, granted April 4, 1944.

An object of the invention has been to provide simple but effective, conveniently located, and readily operable presser foot lifting devices in a machine which is substantially completely enclosed to facilitate lubrication.

The invention is especially concerned with a machine having a hollow frame comprising a base or work supporting member, a vertical standard and an overhanging arm, carrying a needle head at its outer end. The needle head is equipped with vertically movable needle and presser bars. A part of the setting for the invention is the provision of means within such a machine for distributing a fine mist or spray of lubricating oil within the hollow frame and delivering said oil to various operating parts including the mechanism in the needle head. Another feature is the provision in such a machine of a presser bar lifting mechanism including a rock shaft extending longitudinally through the interior of the upper, hollow arm. Connections are provided from one end of the rock shaft, within the needle head, to the presser bar and connections are provided adjacent the other end of said shaft, at or near the hollow standard, for imparting a rocking movement to the shaft whenever it is desired to lift the presser bar. As a special advantageous feature of this construction, the connections for operating the rock shaft include a lever which is passed through the wall of the upper, hollow arm at a recess in the latter adjacent a bearing for the inner end of the shaft.

Another object of the invention has been to provide an enclosure for all of the moving parts of the machine, except those acting directly upon the work being sewed and those requiring manipulation from the outside, and to place these in protecting recesses, so as to avoid projections, particularly of moving parts, which might cause injury to the operators or with which the work might catch and become torn. Toward this end the means for operating the lever connected with the rock shaft includes a thrust bar extending downwardly from said lever through an opening in an overhanging portion of the work support, and attached at its lower end to a rock member mounted in a recessed or set-in portion of the

2

base beneath the work support. Suitable connections are provided for rocking said member by a foot treadle or the like.

Other objects, features and advantages of the invention will appear from a detailed description of an illustrative embodiment of the same which will now be given in conjunction with the accompanying drawings, in which:

Fig. I is a view in vertical longitudinal section of a lock stitch sewing machine embodying the present invention.

Fig. II shows the machine in top plan.

Fig. III is a horizontal section taken in a plane below the level of the work support of the machine.

Fig. IV is a view partly in elevation and partly in cross section, taken as approximately indicated by the angled arrows in Figs. I and III, with the cover of the needle head removed to expose the parts at the interior, and

Fig. V shows the machine in rear end elevation with portions broken out and shown in section to better illustrate important details of the frame construction.

With reference first more particularly to Figs. I to IV, it will be observed that the machine chosen for exemplification of my invention has a hollow work-supporting base 1 with a top wall 2, front and rear side walls 3 and 4 and ends walls 5 and 6. The hollow 1 of the base 1 is closed at the bottom, with interposition of a sealing gasket 8, by a removable cover plate 9 and is employed as a sump for oil which is normally maintained at the level indicated at L. Rising from the base 1 at one end is a hollow standard 10, which, at the bottom, communicates directly with the chamber 7 and with which is integrally formed a hollow arm 11. As shown, the arm 11 overreaches the base 1 and terminates at its free end in a hollow head 12. A crosswise partition 13 isolates the hollow of the head 12 from the hollow of the arm 11, which latter, at its rear end, communicates directly with the hollow of the standard 10, as best shown in Fig. I. Extending longitudinally through the arm 11 and journaled in bushings 15 and 16, set, respectively, into the partition 13 and the rear wall of the standard 10 is a rotary shaft 17. As shown, this shaft 17 protrudes to the exterior of the frame arm at its right hand end and at its outer end carries a combined hand and belt wheel 18 by which the machine may be operated either manually or under power.

Confined to axial reciprocation in bushings 19 and 20, respectively, at the top and bottom of the

head 12, is a bar 21, which, at its lower end, carries a needle 22. Through a link connection 23 with a crank pin 25 on a disk 26 at the end of the shaft 17 within the hollow of the head 12 the needle bar 21 is given its reciprocating motion. Rotation of the needle bar 21 within its bearings is prevented through engagement of the outer end of the lower pivot pin 27 for the link 23 in a vertically-grooved guide 28 interiorly of the head 12. From Fig. I it will be noted that the drive shaft 17 also has journal support in a sleeve 29 set into a pendant bearing lug 30 within the hollow of the needle arm 11. As shown in Fig. III, the end wall 5 of the base is angularly recessed as at 35 to accommodate the loop taker of the machine, which, in this instance, has the form of a rotary hook 36 and which cooperates with the needle 22 beneath the work support 2 in stitch formation. The rotary hook 36 is secured to the protruding end of a shaft 37 which extends through a bearing sleeve 38 fixed in the end wall 5 of the base. Within the chamber 7, the sleeve is supported in a bearing lug 39 pendant from the top wall 2 of the base (see Figs. I and III) while the inner end of the hook shaft 37 extending beyond the sleeve is journaled in a shorter sleeve or bushing 38a set into another pendant lug 40 within said base spaced from the lug 39. Through a pair of intermeshing spur gears 41 and 42, the hook shaft 37 is driven from a rotary shaft 43 which extends longitudinally of the chamber 7 and which is journaled in bearings, respectively, provided by the end wall 5, the lug 39 and a web projection 45 extending forwardly from the rear wall 4 within the base. By means of a train of intermeshing spur gears 46, 47 and 48 within the hollow of the standard 10, the lower shaft 43 is driven from the upper shaft 17 in the same direction and at the same speed. It is, however, to be noted that the ratio of the spur gears 41 and 42 is such as to impart two revolutions to the hook shaft 37 for each revolution of the upper shaft 17 from which the needle bar 21 is actuated.

The feed mechanism of the machine includes a feed dog 50, the teeth of which operate upwardly through slots 51 in a throat plate 52 set into the inner end of a cut-out 53 in a cover plate 54, which is in turn set into a depression 55 in the upper surface of the top wall 2 of the base 1 at the front end of the latter (see Figs. I, II and IV). From Fig. IV it will be observed that the feed dog 50 is secured, with capacity for vertical adjustment, to a carrier 56 having a cylindric shank which extends inwardly through a clearance opening 57 in the longitudinally offset portion 58 of the end wall 5 of the base 1. The inner end of the carrier bar 56 is secured by set screws 59 in a socket member 60 having a transverse boss 61 (see also Fig. III) in which a pin 62 is in turn secured for pivotal connection to the top of a rocker 63. This rocker 63 reaches upwardly from a rock shaft 65 journaled at its opposite ends in bushings 66 and 67, respectively, set into the end wall 5 of the base and into the laterally offset portion 68 of the rear wall 4. Also secured to the rock shaft 65 within the chamber 7 is an upwardly extending arm 69, which, through a telescopic link 70, is connected to the strap 71 of an actuating eccentric 72 on the shaft 43. Under the influence of the eccentric 72 and the interposed parts just described, horizontal feeding movements are imparted to the feed dog 50. The means for regulating the feed throw of the feed dog 50 includes a regulating shaft 75 (Figs. III and V) which is journaled in the lugs 39 and 45

hereinbefore referred to. An arm 76 on the left hand end (Fig. III) of the regulating shaft 75 is connected by a "lazy" bar 77 to a stud 78 on the sleeve member of the telescopic link 70. At its right hand end beyond the bearing lug 45, the shaft 75 is provided with another arm 79 which is urged counter-clockwise, as viewed from the right in Fig. III (see also Fig. V), by a torsion spring 80 and against which the inner end of an adjusting rod 81 abuts. As shown in Fig. V, the rod 81 has a screw-thread engagement with a lug 82 within the base 1 and extends at an inclination through the front wall of the standard 10 to the exterior. At its outer end the rod 81 is provided with a knurled manipulating head 83. For further details as to the arrangement and operation of the rod 81 and other parts of the feed regulating means, reference may be had to the patent to Sauer and Smith, No. 2,035,508, granted on March 31, 1936. Lifting and lowering movements are imparted to the feed dog 50 from a crank 85 at the outer (left hand) end (Fig. III) of the lower shaft 43, said crank being connected through a vertical link 86 with a curved depending arm 87 (Fig. IV) on the carrier 56 for the feed dog 50. The construction and operation of the entire feed mechanism just described is substantially identical with that disclosed in the above-mentioned Sauer and Smith patent, to which reference may be had for details if found necessary.

In its feeding action, the dog 50 reacts with a presser foot 90 pivotally connected to a shank member 91 at the lower end of a presser bar 92. As shown in Fig. IV, the presser bar 92 extends up through a bearing in the bottom of the needle head 12, and, within the hollow of the latter, carries a collar 93 against which the lower end of a helical compression spring 95 bears. At its top, the spring 95 abuts the upper bearing sleeve 96 for the rod 92, which sleeve is threaded for adjustment in the needle head 12 so that the pressure of the spring may be regulated as desired or required.

In order that the presser foot 90 may be raised to facilitate insertion of the work beneath it initially, there is provided a control mechanism including a shaft 97 within the hollow of the overhanging arm 11, said shaft being journaled at its opposite ends in the partition 13 and in the lug 30, respectively. The left hand end of the shaft 97 (Fig. I) extends through the partition 13 into the hollow of the needle head 12 and there has an arm 98 (Fig. IV), which, through a link 99, is connected to a collar 93a which is slidable on the presser bar, and which is normally spaced from the lower face of the collar 93, so that during the operation of the machine, the presser bar is subject only to the influence of the spring 95. A torsion spring 100 surrounding the end of the shaft 97 within the head 12 tends to rotate said shaft clockwise in Fig. IV and through the link 99 causes the loosely mounted collar 93a on the presser bar 92 to be normally held in its lower position in engagement with the bottom of the needle head 12 and away from collar 93. Secured to the shaft 97 within a lateral recess 101 in the lug 30 in the hollow of the frame arm 11 (Figs. I, II and V), is an operating lever 102 which reaches outward from said arm for connection to a pendant link rod 103. This link rod 103 passes through a guide hole in the work support 2 and is connected at its lower end to one extremity of a motion translating lever 105 fulcrumed on a fixed stud 106 which extends outward from the

inwardly recessed portion 107 of the rear side wall 4 of the base 1. The other extremity of the lever 105 is engaged from beneath by a pad at the top of the thrust rod 108 which may extend to an actuating knee press or foot treadle, not illustrated. Due to the lateral recessing of the side wall 4, it will be seen that the presser foot control connections are kept within the confines of the work support 2 with consequent avoidance of projections therebeyond.

As previously pointed out, the hollow of the base 1 of the machine is utilized as an oil sump. For the purpose of circulating the oil within the machine to lubricate the various enclosed parts, the oil is lifted from the supply as a consequence of the dipping thereinto of the gear 48 on the lower shaft 43. The oil thus lifted is further carried up by the gears 47, 46 and, by the high speed rotation of the latter, dispersed in the form of a mist within the hollow of the standard 10 and the connecting hollow of the frame arm 11. Some of this dispersed oil finds its way into a pocket 110 (Fig. I) at the top of the right hand end bearing 16 for the drive shaft 17 and is conducted through a port 111 to the shaft surface within said bearing, any excess oil being returned into the base by way of a duct 112 at the bottom of said bearing. Part of the dispersed oil is also caught by the open rear end 113 of a tube 115 which extends horizontally forward within the hollow of the frame arm 11 and through the partition 13 into the needle head 12. Wick filled tubes 116, 117 and 118 lead from the delivery end of the tube 115 and release oil from above onto the moving parts within the needle head 12. The excess oil thrown off by the needle operating mechanism is collected in a small sump 119 in the bottom of the needle head 12. Connecting with this sump 119 is an inclined duct 120 which leads upward to a lateral port 121 in the left hand end bearing bushing 15 for the shaft 17, which shaft, as shown in Fig. I, is formed within the confines of said bearing with two relatively wide interlapping spiral grooves 122 pitched in one direction and also with a shorter and narrower oppositely pitched groove 123. As the shaft 17 rotates, the helical groove 122 functions as a pump to constantly lift the accumulating oil from the sump 119 in the needle head through the duct 120 into the bearing 115 to lubricate it and to discharge the excess from said bearing into the hollow of the frame arm 11 wherefrom it drains along the downwardly inclined slope at the bottom of said arm back into the base 1. At the same time, the smaller reversely pitched groove 123 slightly opposes the action of the longer groove 122 to maintain an oil seal within the bearing 15 and thus prevents air pumping when the shaft becomes worn. Some of the dispersed oil is, moreover, caught in a well 125 (Fig. I) integrally formed with the machine frame within the standard 10 above the lower shaft 43. Leading horizontally from the well 125 through the top wall 2 of the machine base 1 is a duct 126 which delivers into a channel 128 formed in the depressed free end portion 55 of said top wall.

As set forth in detail in said parent application, provision is made for the distribution of lubricant from the channel 128 to various bearing surfaces of the shafts 37 and 43, the gears 41 and 42, and the work feeding mechanism. The right hand end bearing 45 for the shaft 43 is lubricated by oil passing directly down through a duct 45a from the wall 125.

The excess oil dripping from the lubricated parts drips back into the main supply within the bottom of the base 1 and is recirculated by the action of the gears 46-48. In order that the oil level in the base of the machine may be checked from time to time, there is provided a gauge rod 160 which extends down into the base 1 and which at its top has a knob 161 accessible for convenience of grasping it within a recess 162 formed in the walls of the standard 10 (see Figs. I and IV). Leakage of oil from the base 1 at the clearance opening 57 through which the feed dog carrier 56 extends is prevented by a moving sealing means 163 which, as shown in Figs. III and IV, comprises a plurality of washers 165 which snugly surround the cylindric shank of the carrier 56 and which are pressed against the face of a machined recess 166 in the inner side of the wall 58 by a leaf spring 167. At its lower end the spring 167 is secured to the wall portion 58, and at its upper end is bifurcated to straddle the shank of the feed dog carrier bar 56.

In order that the more delicate parts of the rotary hook 36 may be lubricated with a different, lighter grade of oil from that used for the other moving parts of the machine, there is provided a separate source of supply for such oil in the form of a glass gravity feed cup, which is shown at 170 in Figs. II, IV and V as being mounted on the top of the base 1 in the rear of the standard 10. At the bottom, the cup 170 communicates with a vertical duct 171 in an enlargement 172 at one corner of the base 1 within the chamber 7. Leading from the duct 171 within the chamber 7 is a tube 173 by which the oil from the cup 170 is conducted to a nipple 175 screwed axially into the inner or cap bearing for the hook shaft 37 as shown in Figs. I and III. As further shown in Fig. I, the hook shaft 37 is hollow and open within its inner bearing to receive the oil conveyed into said bearing by the tube 173. The internal construction of the rotary hook 36 may be as shown in U. S. Patent No. 2,035,984 granted to George Sauer on March 31, 1936, so that the oil may reach the bearing surfaces between its rotating and non-rotating parts. As a means for controlling the flow of oil to the rotary hook, there is provided a regulating screw 175a which engages radially into a collar enlargement 176 on the hook shaft 37 immediately behind the hook and externally of the end wall 5 of the base 1. As shown, the inner end of the screw 175a is diametrically reduced and passes into the duct of the hook shaft 55 to partially obstruct said duct. This construction is advantageous not only by reason of its simplicity but in that it permits accurate adjustment of the oil flow to the hook without necessitating disassembling of the latter for the purpose.

While an illustrative embodiment of the invention has been set forth in considerable detail, it will be understood that numerous changes may be made in the construction, combination and arrangement of the various parts without departing from the principles and scope of the invention.

I claim:

1. In a sewing machine having a frame with a hollow work supporting base containing a supply of lubricating oil, and a hollow overhanging arm sustained by a hollow standard at one end of said base, the hollows of said base, arm and standard being intercommunicating, needle operating mechanism in a head at the free end of

the frame arm, and means for elevating oil from the supply and dispersing it as a mist within the standard for lubricating moving parts within the frame, the combination of a presser bar confined to up and down movement in the needle head, and means for lifting the presser bar including a horizontal rock shaft journaled in a bearing lug within the frame arm adjacent the upper end of said standard, a lifting arm on the shaft within the needle head and connected to the presser bar, an operating lever connected to the shaft in a recess opening into the frame arm in the bearing lug aforesaid and extending outward from said recess, the rear wall of the base being inwardly recessed, said recessed portion being overhung by the top wall of the base, a motion translating lever fulcrumed intermediate its ends on a stud projecting outward from the recessed wall portion of the base, said operating lever on the rock shaft extending laterally from the frame arm, a thrust bar extending down from the operating lever and through a guide hole in the overhanging portion of the work support to one extremity of the motion translating lever, and means enabling the connection of the other extremity of the motion translating lever to an actuating knee press or foot treadle.

2. In a sewing machine having a hollow frame with a work supporting member, a vertical standard and an overhanging arm in intercommunication, said arm carrying a needle head at its free end, the lower portion of said frame being formed to provide a lubricant sump from which oil may be dispersed through said frame, the combination of a presser bar movable up and down in

said needle head, a rock shaft extending longitudinally within said arm, connections from said shaft to said presser bar for lifting the same, an operating member connected with said rock shaft and extending through a substantially sealed opening in a wall of said overhanging arm, said work supporting member being externally recessed in its rear wall at a point beyond the normal path of travel of the work passing over said supporting member and having an aperture through its work supporting surface in the region of said recess, a rock member mounted on said work supporting member in said recess and arranged to be operated at will, and a link passing through said aperture connected at its opposite ends with said rock member and with said operating member.

3. In a sewing machine, a hollow frame comprising a base, a standard rising from one end of the base, and an overhanging arm extending from said standard over said base and carrying a needle head at its end, said base comprising an enclosed housing having a generally rectangular outline in plan but having an external recess in one side, a presser bar movable up and down in said needle head, and means for lifting said presser bar comprising a rock member mounted in said recess in said side of the base exteriorly of the enclosed housing, a link connected with said member extending along said standard, a rock shaft within said arm connected at one end with said link and at its other end with said presser bar, and spring means operable to hold said presser bar lifting means normally in an idle position.

OSCAR QUIST.
